UNITED STATES PATENT OFFICE.

ALFRED JOHNSON, OF GRAFTON, NORTH DAKOTA.

LOCOMOTIVE ATTACHMENT.

1,324,158.

Specification of Letters Patent.

Patented Dec. 9, 1919.

Application filed January 10, 1919. Serial No. 270,519.

To all whom it may concern:

Be it known that I, ALFRED JOHNSON, a citizen of the United States, residing at Grafton, in the county of Walsh and State 5 of North Dakota, have invented certain new and useful Improvements in Locomotive Attachments; and I do hereby declare the following to be a full, clear, and exact description of the invention, such as will enable others skilled in the art to which it 10 appertains to make and use the same.

This invention relates to locomotive attachments, and the primary object of the invention is to provide an improved means 15 for conducting the smoke and cinders from the smoke stack of the engine to a point below the locomotive body, so as to eliminate cinders from falling upon the railroad coaches and upon objects along side of the 20 railroad track, so as to prevent the possibility of the same being put on fire by the live cinders.

Another object of the invention is to provide means for extending a cinder and smoke 25 conductor through the tender of the locomotive, so as to preheat the feed water for the locomotive prior to its entrance into the boiler.

A further object of the invention is to provide an improved means for arranging the 30 smoke and cinder pipes in the tender, so as to increase the radiating surface thereof and provide means for allowing the condensation of water in the smoke and cinder 35 pipes to fall into the tender.

A still further object of the invention is to provide an electrically operated fan in the smoke and cinder conducting pipes so as to effectively increase the draft of the 40 locomotive.

A still further object of the invention is to provide an improved device of the above character, which is durable and efficient in use, one that is simple and easy to manufacture, and one that can be applied to the 45 ordinary type of locomotive without materially changing the construction thereof.

With these and other objects in view the invention consists in the novel construction, 50 arrangement, and formation of parts, as will be hereinafter more specifically described, claimed and illustrated in the accompanying drawings, forming a part thereof, in which:—

55 Figure 1 is a side elevation of the locomotive and tender showing the improved

smoke and cinder conductor attached thereto,

Fig. 2 is a plan view of the same,

Fig. 3 is a front elevation of the locomotive showing the arrangement of the smoke conductor pipes,

Fig. 4 is a detail cross section taken through the smoke conductor, and

Fig. 5 is a detail cross section through the locomotive tender.

Fig. 6 is a section taken on the line 6—6 of Fig. 4.

Referring to the drawings in detail, wherein similar reference characters designate 70 corresponding parts, throughout the several views, the numeral 1 indicates the improved smoke conductor which is adapted to be secured to the smoke stack 2 of an ordinary locomotive 3. The locomotive 3 75 includes the boiler 4 and cab 5. A tender 6 is secured to the locomotive 3 in the ordinary manner.

The smoke conductor 1 includes a downwardly and rearwardly inclined pipe 7, 80 preferably circular in cross section which has the upper end thereof secured to the smoke stack intermediate its ends. The smoke stack 2 is provided with an opening 8 which forms an entrance for the smoke and 85 cinders from the smoke stack into the pipe 7.

The lower end of the pipe 7 is contracted as at 9 and terminates in a pair of relatively small conductor pipes 10 and 11 which converge outwardly and rearwardly from the 90 pipe 7. The pipes 10 and 11 are curved downwardly as at 12 over each side of the boiler 4 and are then bent rearwardly as at 14. The pipes 10 and 11 extend on each side of the boiler and project beyond the 95 cab 5, and are connected to sections 15 and 16 by flexible couplings 17. The sections 15 and 16 extend into the tender 6 and through the water tank 18 thereof. The pipes 10 and 11 and the sections 14 and 15 are inclined 100 downwardly and rearwardly from the bend 12 as shown in Fig. 1 of the drawings. The pipes 9, 10 and 11 may be formed either of a continuous length of tubing or in a plurality of sections suitably connected as 105 desired. The sections 15 and 16 have connected thereto upwardly extending vertical pipes 19 and 20 which have their upper ends connected to forwardly and upwardly inclined pipes 21 and 22 which extend through 110 the water tank 18 above the water line thereof. The pipes 21 and 22 extend forwardly

of the tender 6 and are connected to the downwardly extending vertical pipes 23 and 24, which terminate below the tender and form means for conveying the cinders and smoke below the locomotive and tender and onto the railroad tracks. The lower surfaces of the pipes 21 and 22 are provided with a plurality of relatively small openings 25 which permit of any water or condensation 10 to drop into the water tank 18. By forming the smoke conductor pipes into a pair of sections and extending the sections to the water tank of the tender at each side thereof, the water in the tender is preheated prior 15 to its entrance into the boiler. The heat radiating surface of the sections are also increased by extending the pipes upwardly and then forwardly through the tender, so as to provide a tortuous course for the cinders and smoke to the water tank.

It also can be seen that the hot gases can escape through the openings 25 in the pipes 21 and 22 so that they may act directly upon the feed water.

25 A fan 26 is rotatably mounted in the pipe 7 and is preferably driven by an electric motor 22 which obtains its power from a storage battery or other suitable source. The fan 26 provides a forced draft for the locomotive for sweeping the smoke and cinders through the pipes 7, 10, 11, and sections 30 15 and 16.

A damper 28 is positioned in the smoke stack 2 above the opening 8 and is operated 35 by a handle 29 which forms means for closing the upper end of the smoke stack so as to direct the smoke and cinders into the pipe 7. When the engine is first started the damper 28 is preferably opened so as to 40 allow the smoke to pass directly through the smoke stack.

From the foregoing description it can be seen that an improved smoke and cinder conductor is provided for locomotives whereby 45 the cinders and smoke are guided below the train and onto the railroad tracks, the conductor being so arranged as to form a feed water heater for the locomotive. While the smoke conductor has been shown and described in use with locomotives, it is understood that the same can be used with equal 50 success on stationary engines.

In practice, I have found that the form of 55 my invention, illustrated in the accompanying drawings and referred to in the above description, as the preferred embodiment, is the most efficient and practical; yet realizing the conditions concurrent with the adoption of my device will necessarily vary, I 60 desire to emphasize the fact that various minor changes in details of construction, proportion and arrangement of parts may be resorted to, when required without sacrificing any of the advantages of my invention as set forth.

What I claim as new is:—

1. In a device of the class described, the combination with a locomotive including a boiler and smoke stack, of a conductor secured to and extending rearwardly from the smoke stack, a pair of rearwardly diverging pipes secured to the conductor, said pipes being inclined downwardly and rearwardly and extending on each side of the boiler, and a fan rotatably mounted in the 75 conductor pipe.

2. In a device of the class described, the combination with a locomotive including a boiler and smoke stack, said smoke stack having an opening formed therein intermediate the ends thereof, a relatively large conductor pipe secured to the walls of the opening and communicating with the smoke stack, said conductor pipe being extended rearwardly and downwardly and 80 having the lower terminal thereof contracted, a pair of diverging ducts secured to the contracted end of and communicating with the relatively large conductor pipe, said ducts being inclined downwardly and rearwardly and terminating below the locomotive body, and a damper in said smokestack positioned intermediate the upper end thereof and the opening.

3. In a device of the class described the combination with a locomotive including a smoke stack and boiler, said smoke stack having an opening formed therein intermediate the ends thereof, a relatively large conductor pipe secured to the walls of the 100 opening and communicating with the smoke stack, said conductor pipe being extended downwardly and rearwardly and having the lower end thereof contracted, a pair of diverging ducts secured to the contracted 105 end of the conductor pipe, said pipe being extended downwardly and rearwardly, a fan rotatably mounted in the conductor pipe, and a damper rotatably mounted in the smoke stack and positioned intermediate 110 the upper end thereof and the opening, as and for the purpose specified.

4. In a device of the class described, the combination with a locomotive and tender including a boiler and smoke stack, a relatively large conductor pipe secured to and communicating with the smoke stack, the lower terminal of the conductor pipe being contracted, a pair of rearwardly diverging ducts secured to the contracted end of 120 the conductor pipe, said ducts being extended through the tender.

5. In a device of the class described, the combination with a locomotive including a boiler and smoke stack and a tender, of a 125 relatively large conductor pipe secured to and communicating with the smoke stack, the lower terminal of the smoke pipe being contracted and provided with a pair of rearwardly and downwardly inclined 130

ducts, the ducts being positioned at each side of the locomotive boiler and extended through the tender, vertical branch pipes extending to the ducts, forwardly and upwardly inclined pipes secured to the upper ends of the vertical pipes and lying substantially parallel to the ducts, and downwardly extending pipes secured to the last mentioned pipes and have the terminals

thereof positioned below the locomotive tender, said upwardly inclined pipe being perforated, as and for the purpose specified.

In testimony whereof I affix my signature in presence of two witnesses.

ALFRED JOHNSON.
